DESIGN FOR A CARPET.

SPECIFICATION forming part of Design No. 19,011, dated April 9, 1889.

Application filed March 7, 1889. Serial No. 302,343. Term of patent 3½ years.

To all whom it may concern:

Be it known that I, JAMES L. FOLSOM, a citizen of the United States, residing in Brooklyn, county of Kings, and State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design is composed of a body, A, and a border, B. The body A is composed of a succession of large circular flower forms resembling dahlias, shown as partly overlapping

one another. The border B has a middle portion formed by a succession of similar flower forms. Below this is a narrow ornamental margin, and above it is a wider margin ornamented with small flower and leaf forms and conventional figures. 20

What I claim as new, and desire to secure by Letters Patent, is— 25

1. The design for a carpet, consisting of the body A, substantially as shown.
2. The design for a carpet, consisting of the border B, substantially as shown.
3. The design for a carpet, consisting of the body A and the border B, substantially as shown.

JAS. L. FOLSOM.
